(57) **CLAIM**

The ornamental design for a pet toy, as shown and described.

DESCRIPTION

FIG. 1 is a generally front right perspective view of a pet toy showing our new design;

FIG. 2 is a front view of the pet toy shown in FIG. 1;

FIG. 3 is a rear view of the pet toy shown in FIG. 1;

FIG. 4 is a top view of the pet toy shown in FIG. 1, which is the same as the bottom view rotated one hundred eighty degrees;

FIG. 5 is a left side view of the pet toy shown in FIG. 1, which is the same as the right side view rotated one hundred eighty degrees;

FIG. 6 is a generally front right perspective view of a second embodiment of the pet toy showing our new design;

FIG. 7 is a front view of the pet toy shown in FIG. 6;

FIG. 8 is a rear view of the pet toy shown in FIG. 6;

FIG. 9 is a top view of the pet toy shown in FIG. 6, which is the same as the bottom view rotated one hundred eighty degrees; and,

FIG. 10 is a left side view of the pet toy shown in FIG. 6, which is the same as the right side view rotated one hundred eighty degrees.
